UNITED STATES PATENT OFFICE

2,431,872

MOLD VIBRATOR

Alex Kavula, Cleveland, Ohio

Application May 16, 1944, Serial No. 535,863

6 Claims. (Cl. 259—75)

1

The present invention relates to a mold vibrator and has for its prime object to provide a machine for oscillating a mold while hot metal is being poured therein thereby causing all impurities to be forced to the top.

Another important object of the invention resides in the provision of a machine of this nature which is comparatively simple in its construction, compact and convenient in its arrangement of parts, easy to manipulate, thoroughly efficient and reliable in use and operation and otherwise well adapted to the purpose for which it is designed.

With the above and numerous other objects in view as will appear as the description proceeds, the invention consists in certain novel features of construction, and in the combination and arrangement of parts as will be hereinafter more fully described and claimed.

In the drawings:

Figure 1 is a side elevation of a machine embodying the features of my invention.

Figure 2 is a top plan view thereof.

Figure 3 is a vertical section through the mold.

Figure 4 is a detail section through one of the connecting rods and cams taken substantially on the line 4—4 of Figure 2.

Figure 5 is a bottom plan view of the mold base.

Figure 6 is a sectional view taken substantially on the line 6—6 of Figure 3 with the ball bearings removed.

Figure 7 is a detail section taken substantially on the line 7—7 of Figure 2.

Figure 8 is a sectional view through one of the cams taken substantially on the line 8—8 of Figure 2.

Figure 9 is a top plan view of one of the sections of one of the connecting rods.

Figure 10 is a perspective view of another section thereof, and

Figure 11 is a sectional view taken substantially on the line 11—11 of Figure 4.

Referring to the drawing in detail it will be seen that the numeral 5 denotes a car platform mounted on wheels 6 adapted to ride on rails 7. The platform is provided with an oblong opening 8 with an annular ball bearing race 9 disposed thereabout. Numeral 10 denotes a mold base the bottom of which is provided with an annular race 11 of such a size to register with the race 9 and from the center of the bottom projects a pintle 12 with oppositely disposed ribs 14. The pintle with its ribs extends into the oblong opening. Ball bearings 15 are mounted in the races 9 and 11. Thus the base may oscillate on the platform 5 and is limited by the abutment of the ribs 14

2

with sides of the opening 8 as is best illustrated in Figure 6. The platform is provided with a groove 17. The latch 18 is mounted in a recess 19 in the base 10 on a shaft 20 journalled in the base and extending beyond one side edge thereof and having a lever 21 fixed thereto which may be actuated to project the latch 18 into the groove 17 to prevent oscillation of the base on the platform or may be actuated to swing the latch out of the groove. On opposite sides the base 10 is provided with eyes 22.

A shaft 23 is journalled in stands 24 and has keyed thereto as at 25 cams 26. These two cams 26 are oppositely disposed as is indicated to advantage in Figure 1. Cam rings including sections 27 and cams 28 are disposed about the cams and the caps are secured to the sections 27 by means of bolts 29. The sections 27 have each a pair of ears 30. Connecting rods, each consist of a section 31 extending between the ears 30 and swingable on a bolt 32 in the ears. A channel member 33 is bolted as at 34 on the section 31. An arm 35 has one end portion extending into the channel sections 33 and held adjustably in place by means of wedge shaped pins 36 extending through registering openings in the channel section and the arm 35. The other end of the arm 35 has its intermediate portion offset outwardly as indicated to advantage in Figure 2 and the ends terminate in laterally extending pins 38 adapted to be engaged in the eyes 22. When the shaft 23 is in rotation obviously the cams cooperating with the connecting rod imparts an oscillatory movement to the mold base.

Cables 40 may be engaged by eye bolts 41 with the connecting rods and extended over suitably mounted pulleys 41' and weights 42 may be mounted on the ends of the cables to hold the connecting rods in a raised out of the way position when desired.

Numeral 43 denotes the mold which at its bottom is provided on opposite sides with outwardly extending lugs 44 disposed between lugs 45 rising from the base 10 in pairs, one pair for each lug 44 and wedge pins extend through openings in the lugs 45 over the lugs 44 thereby securing firmly the mold to the base.

When the machine is started, it oscillates the mold and the hot metal is poured into the mold. All the impurities are forced to the top and the machine is kept in motion until the metal is solid. in Figure 3 I have indicated the ingot formed in the mold 43. Numeral 46 denotes the ingot and numeral 47 indicates the defect at the top thereof. It is thought that the construction, operation,

utility and advantages of this invention will now be clearly understood by those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit and scope of the invention as hereinafter claimed or sacrificing any of its advantages.

Having thus described my invention, what I claim as new is:

1. A machine of the class described including a platform, a mold-carrying base mounted on the platform for oscillation thereon, a shaft, a pair of cams mounted on the shaft and disposed in opposite directions, connecting rods, rings on the connecting rod circumjacent the cams, said connecting rods having ends terminating in pins, and said base having eyes to receive said pins, a pulley, a cable trained over the pulley, a weight on one end of the cable, and means for engaging the other end of the cable with one of the connecting rods.

2. In combination, track rails, a car movable on said track rails and including a wheeled platform provided with an annular race in the upper surface thereof and having an elongated opening therein centrally of the race, a mold carrying base having a second race in the bottom surface thereof and provided centrally of said second race with a depending pintle received in said opening of the platform, lugs on the pintle co-acting with walls of the opening to limit oscillation of the base about the vertical axis of said pintle, ball bearings interposed between the platform and the mold base and disposed in said races, and oscillating means for the base including a connecting rod detachably connected to the base and means for reciprocating said connecting rod mounted beside the track rails.

3. In combination, track rails, a car movable on said track rails and including a wheeled platform, a mold-carrying base mounted on said platform for oscillation about its vertical axis, and oscillating means for the base including a con-

nnecting rod detachably connected to the base and means for reciprocating said connecting rod mounted beside the track rails.

4. In combination, track rails, a car movable on said track rails and including a wheeled platform, a mold-carrying base mounted on said platform for oscillation about its vertical axis, and oscillating means for the base including a connecting rod detachably connected to the base and means for reciprocating said connecting rod mounted beside the track rails, said connecting rod being swingable upwardly when disconnected from the base, and yieldable means to hold the connecting rod in upwardly swung position.

5. In combination, track rails, a car movable on said track rails and including a wheeled platform, a mold-carrying base mounted on said platform for oscillation about its vertical axis, and oscillating means for the base including a connecting rod detachably connected to the base and means for reciprocating said connecting rod mounted beside the track rails, and manually releasable means to prevent oscillation of the base relative to the platform.

6. In combination, track rails, a car movable on said track rails and including a wheeled platform, a mold-carrying base mounted on said platform for oscillation about its vertical axis, and oscillating means for the base including an extensible connecting rod detachably connected to the base and means for reciprocating said connecting rod mounted beside the track rails.

ALEX KAVULA.
